United States Patent Office.

WILLIAM H. GROESBECK, OF SARATOGA SPRINGS, NEW YORK.

Letters Patent No. 102,935, dated May 10, 1870.

IMPROVED HOLD-BACK FOR VEHICLES.

The Schedule referred to in these Letters Patent and making part of the same.

To all whom it may concern:

Be it known that I, WILLIAM H. GROESBECK, of Saratoga Springs, in the county of Saratoga and State of New York, have invented certain new and useful Improvements in Hold-backs; and I do hereby declare that the following is a full, clear, and exact description thereof, reference being had to the accompanying drawings and to the letters of reference marked thereon, which form a part of this specification.

The nature of my invention consists in the construction and arrangement of a metal "hold-back" to be attached to shafts of vehicles.

In order to enable others skilled in the art to which my invention appertains to make and use the same, I will now proceed to describe its construction and operation, referring to the annexed drawings, in which—

Figure 1 is a side view of a horse, showing the application of my invention, and

Figure 2 is a longitudinal vertical section of the "holdback."

A represents the shaft of a vehicle, to the under side of which is secured a plate, B, by means of a screw at each end.

From near the rear end of this plate, a hook, C, projects downward and forward, said hook and plate being cast in one piece.

Near the front end of the plate B, in a slot in the same, is pivoted a tongue, D, the lower end of which is pressed against the lower front end of the hook C by the following means:

In a recess in the upper side of the plate B is placed a rod, a, having a shoulder or enlargement, b, at its front end, which bears against a projecting shoulder, d, on the upper end of the tongue D.

Around the rod a is a spiral spring, e, which presses the rod forward, keeping the tongue D pressed against the hook C, as shown in fig. 2.

The tongue D is readily lifted forward, and the breeching-strap of the harness hooked in the hook C, and the tongue D closes, holding it there.

Having thus fully described my invention,

What I claim as new, and desire to secure by Letters Patent, is—

The tongue D, provided with projection d, in combination with rod a, spiral spring e, hook C, and plate B, all constructed and arranged to operate as and for the purpose described.

In testimony that I claim the foregoing as my own, I affix my signature in presence of two witnesses.

W. H. GROESBECK.
